ELECTRICAL SWITCH

Olav Froland, St. Louis, Mo., assignor to James R. Kearney Corporation, St. Louis, Mo., a corporation of Missouri

Application February 23, 1937, Serial No. 127,077

6 Claims. (Cl. 200—48)

This invention relates generally to electrical switches, and more specifically to electrical switches intended particularly for use as parts of gang-operated switch structures adapted for dis- 5 position adjacent to the tops of conductor-supporting poles and operable to simultaneously make and break electrical connections between portions of a plurality of conductor lines, the predominant object of the invention being to provide such a 10 switch structure with substantially rigid means for transmitting electrical energy from one movable part of the switch structure to another movable part thereof whereby the use of loose, flexible connections for this purpose is eliminated.

15 Briefly stated switch structures of the type to which this invention relates comprise a stationary contact assembly and a movable contact assembly, said movable contact assembly usually having associated therewith suitable operating 20 means which provide for movement of the movable contact assembly into and out of electrical association with the stationary contact assembly from a position some distance below the position 25 of the switch structure at the top of a pole. Also ordinarily a switch structure of this description includes a flexible length of cable which is 30 electrically connected to the movable contact assembly and serves as a shunt or jumper for conducting electrical energy from the line conductor with which the switch structure is associated to 35 said movable switch assembly. These flexible lengths of cable are objectionable in the use of switch structures of this type because they are 40 more or less loose and free and produce a loop of considerable proportions when the movable contact assembly is drawn to the open switch position.

The main purpose of this invention, therefore, 45 is to provide an improved switch structure which 50 include improved substantially rigid mechanical means for transmitting electrical energy from the line conductor to the movable contact assembly whereby the use of the objectionable flexible shunt or jumper is entirely eliminated.

45 Fig. 1 is a side elevation of a pole top switch which includes as a part thereof my improved means for transmitting electrical energy from the line conductor with which the switch is associated to the movable contact assembly of the 50 switch, a part of a pole being associated with the switch.

Fig. 2 is an enlarged fragmentary view partly in elevation and partly in section illustrating the improved energy conducting means of the switch 55 illustrated in Fig. 1.

Fig. 3 is a plan view of the structure shown in Fig. 2 a part thereof being shown in section.

Fig. 4 is a perspective of the improved energy conducting means illustrated in Figs. 2 and 3.

For the purpose of this application I have illus- 5 trated the invention in association with a switch unit of a gang-operated switch structure of the type disclosed in an application for United States Letters Patent filed in my name on March 9, 1936, 10 Serial No. 67,807 now Patent No. 2,129,270 issued Sept. 6, 1938, but it is to be understood that the invention is not limited to use with switch structures of this particular type but may be employed 15 with equally efficient results as a part of gang-operated switch structures of different construc- 15 tion and arrangement.

In the drawings, wherein is shown for the purpose of illustration, merely, one embodiment of the invention A designates generally the switch structure illustrated in Fig. 1 which is shown as 20 being mounted at the top of a pole B. As illustrated the switch structure is secured to the pole B through the instrumentality of cross members 1 which are disposed at opposite sides of the pole and are suitably secured thereto. Supported 25 upon and secured to the cross members 1 is a channel beam 2, said channel beam being attached to the cross members 1 by bolts 3.

The particular switch unit illustrated includes 30 a stationary contact assembly Sa and a movable contact assembly Sb, the stationary contact assembly including an insulating member 4 which is secured at its lower end to the upper flange 5 of a bracket 6, and this bracket is secured by bolts 7 to the channel beam 2. The insulating member 35 of the stationary contact assembly is extended upwardly in an inclined plane and secured to said insulating member at its upper end by means of bolts 8 is a contact-supporting plate 9. The contact-supporting plate 9 has mechanically and electrically connected thereto through the instrumentality of a suitable connector 10 an electrical conductor 11.

Extended outwardly from the plate 9 at opposite sides thereof are lugs 12 each of which supports a pair of resilient contact elements 13, each pair of contact elements being secured to the associated lug by a bolt 14 and each contact element being provided with a coll 13' to give to the contact element the required resiliency. The plate 45 9 is provided also with extensions 15 which extend outwardly therefrom in opposite directions and these extensions support rods 16 which serve to limit lateral movement of the contact elements 13.

The movable contact assembly Sb is mounted on a rod 17 which in turn is supported for rocking movement in suitable bearing means 18 secured to the channel beam 2, said movable contact assembly including an insulating member 19 from the lower end of which is extended a clamping means 20 which engages the rod 17 and rigidly secures the movable assembly thereto. The rockable rod 17 also has fixed thereto an arm 21 to the outer end of which is pivotally attached the upper end portion of an operating element 22, said operating element being pivotally attached at 23 to an operating lever 24 which in turn is pivotally connected to a supporting element 25 fixed to the pole B.

Secured to the insulating member of the movable contact assembly Sb is a contact support 26 to which is pivotally attached at 27 a contact 28, said contact being provided with an opening 28' formed therethrough and having laterally extended outwardly projected extensions 29 which are adapted to pass between and make point pressure contact with the pairs of contact elements at opposite sides of the contact-supporting plate 9 of the stationary contact assembly. The contact 28 has associated with it a torsional coil spring 30 which is so arranged that it tends to move said contact to the position in which it is shown by dotted lines at the right hand side of Fig. 1.

In operating the switch unit thus far described from the open switch position of the movable contact assembly Sb as illustrated by dotted lines in Fig. 1 to the closed switch position of said movable contact assembly as shown by full lines in said view, the operator grasps the operating lever and moves it in an upward direction. This transmits rocking movement to the rod 17 and because the movable contact assembly is fixedly mounted on said rod the upper end portion of the movable contact assembly is moved toward the upper end portion of the stationary contact assembly. When the contact 28 of the movable contact assembly Sb is out of contact with the contact elements 13 the torsional coil spring 30 maintains said contact 28 in the position in which it is shown by dotted lines in Fig. 1 and as the movable contact assembly approaches the closed switch position the forward nose portion of the contact 28 strikes the inclined face 31 of the contact-supporting plate 9 of the stationary contact assembly Sa. The outer portion of the contact 28 rides up this inclined face 31 to move the contact 28 to the position in which it is shown by full lines in Fig. 1 whereby the lateral extensions of said contact 28 are forced between the pairs of contact elements 13 at opposite sides of the contact-supporting plate 9 of the stationary contact assembly to make point pressure contact therewith. The stationary contact assembly is provided with a buffer which comprises a headed element 32 with which is associated a shock-absorbing spring 32'. The obvious function of this buffer is to absorb the shock when the movable contact assembly Sb is forcibly moved to the closed switch position, this being accomplished by the extension 28' striking the yieldable buffer 32.

Pivots secured to the contact support 26 by the pivot pin 27 which pivotally attaches the contact 28 to said contact support is a link 33. The link 33 is comprised of a pair of spaced apart elements 33' (Fig. 3) which are joined together by a web of material 34, and as shown in Fig. 1 the web of material referred to is electrically connected to the contact 28 of the movable contact assembly by a flexible conductor 35. The link 33 has pivotally connected

to it at the end thereof which is remote from the end attached to the contact 28 a second link 36 and the opposite end of this link 36 is pivotally attached to a terminal 37 which is supported by and secured to an insulator 38. The insulator 38 is secured to the channel beam 2 through the instrumentality of a bracket 39 to which the insulator is secured and which in turn is secured by bolts 40 to the channel beam 2.

In order to pivotally attach the links 33 and 36 together I prefer to provide the link 33 with integral trunnions 41 which extend outwardly in opposite directions from said link. These trunnions pass through openings formed through spaced apart elements 36' which produce said link 36, and cotter pins or equivalent elements 42 are associated with the trunnions to prevent displacement of the elements 36' of the link 36 therefrom. As shown to the best advantage in Fig. 3 the link 33 is provided with an integral extension 44 which is round in cross-section and extends from one element 33' of the link to the opposed element 33' thereof in alignment with the trunnions 41. In like manner pivotal connection between the link 36 and the terminal 37 is obtained by integral trunnions 45 formed on and extended outwardly from the opposite outer faces of spaced apart legs 37' of the terminal 37, which trunnions pass through apertures formed in the elements 36' of the link 36. Here also cotter pins 46 are associated with the trunnions to prevent displacement of the elements 36' of the link 36 from the trunnions. Likewise an integral extension 37a round in cross-section, is extended from one leg 37' of the terminal 37 to the associated leg 37' thereof in alignment with the trunnions 45.

A conductor 47 is mechanically and electrically connected by means of a suitable connector 48 to the terminal 37, and to provide for good electrical connection between the terminal 37 and the link 33 to which the contact 28 of the movable contact assembly is electrically connected by the connection 35, I provide pairs of rods 49 and 50. These rods are mounted in openings formed in spaced apart blocks 51 and 52 which are interposed between the spaced elements 36' of the link 36. The blocks are secured in place between the spaced elements 36' of the link 36 by screws 53 which pass through openings formed through said spaced elements 36' and are extended into screw-threaded openings 54 formed in the blocks. The opposite end portions of the associated pairs of rods 49 and 50 contact with the extensions 44 and 37a, and as shown clearly in Fig. 2 the opposite end portions of the pairs of rods 49 and 50 are spread apart due to the fact that the extensions 44 and 37a are of a greater diameter than the space between the central portions of the pairs of rods. Because of this arrangement the rods contact with the extensions with considerable compressive force whereby close electrical contact between these parts is provided.

When the switch illustrated in Fig. 1 is in the closed switch position the links 33 and 36 are positioned as shown by full lines in that view, and when the links are so positioned electrical energy passes from the terminal 37, through the rods 49 and 50 to the link 33, and through the flexible connection 35 to the contact 28 of the movable contact assembly. When the movable contact assembly is drawn to the open switch position the links 33 and 36, which produce a toggle, move to the positions in which said link are shown by dotted lines in Fig. 1. During the movement of the

movable contact assembly to the open or closed switch positions the end portions of the pairs of rods 49 and 50 remain in close moving contact with extensions 44 and 31a whereby good electrical contact is provided between the terminal 5 37 and the link 36, and between the link 36 and the link 33, without the use of objectionable loose, flexible cables heretofore employed.

I claim:

- 10 1. An electrical switch comprising a stationary contact assembly, a movable contact assembly, means for moving said movable contact assembly into and out of electrical contact with said stationary contact assembly, a terminal for a line conductor, and means for conducting electrical energy from said terminal to said movable contact assembly, said means comprising a pair of links pivotally connected together and pivotally attached to said terminal and said movable contact assembly, and an elongated, substantially rigid element supported by one of said links and contacting at its opposite ends with a part of the other link and a part of said terminal for conducting electrical energy from said terminal to said other link, said opposite ends of said elongated element being displaced from alignment with the central portion of the elongated element whereby said end portions contact with said parts of said other link and the terminal with considerable 20 compressive force.
- 25 2. An electrical switch comprising a stationary contact assembly, a movable contact assembly, means for moving said movable contact assembly into and out of electrical contact with said stationary contact assembly, a terminal for a line conductor, and means for conducting electrical energy from said terminal to said movable contact assembly, said means comprising a pair of links pivotally connected together and pivotally attached to said terminal and said movable contact assembly, an elongated, substantially rigid element associated with one of said links and contacting at its opposite ends with a part of the other link and a part of said terminal for conducting electrical energy from said terminal to said other link, and a member secured to the link with which the elongated element is associated for supporting said elongated element, said member being provided with an opening through 30 which said elongated element extends.
- 35 3. An electrical switch comprising a stationary contact assembly, a movable contact assembly, means for moving said movable contact assembly into and out of electrical contact with said stationary contact assembly, a terminal for a line conductor, and means for conducting electrical energy from said terminal to said movable contact assembly, said means comprising a pair of links pivotally connected together and pivotally attached to said terminal and said movable contact assembly, and a plurality of elongated, substantially rigid elements supported by one of said links and contacting at their opposite ends with opposite sides of a part of the other link and a part of 40 said terminal for conducting electrical energy from said terminal to said other link, said opposite ends of said elongated elements being displaced out of alignment with the central portions of said elements whereby said ends contact with said parts of said other link and said terminal with considerable compressive force.

4. An electrical switch comprising a stationary contact assembly, a movable contact assembly, means for moving said movable contact assembly into and out of electrical contact with said stationary contact assembly, a terminal for a line conductor, and means for conducting electrical energy from said terminal to said movable contact assembly, said means comprising a pair of links pivotally connected together and pivotally attached to said terminal and said movable contact assembly, a plurality of elongated, substantially rigid elements associated with one of said links and contacting at their opposite ends with opposite sides of a part of the other link and a part of said terminal for conducting electrical energy from said terminal to said other link, and a member secured to the link with which the elongated elements are associated for supporting said elongated elements, said member being provided with openings through which said elongated elements extend.

5. An electrical switch comprising a stationary contact assembly, a movable contact assembly, means for moving said movable contact assembly into and out of electrical contact with said stationary contact assembly, a terminal for a line conductor, and means for conducting electrical energy from said terminal to said movable contact assembly, said means comprising a pair of links pivotally connected together and pivotally attached to said terminal and said movable contact assembly, pairs of elongated, substantially rigid elements associated with one of said links and contacting at their opposite ends with opposite sides of a part of the other link and a part of said terminal for conducting electrical energy from said terminal to said other link, and a member secured to the link with which the elongated elements are associated for supporting said elongated elements, said member being provided with openings through which said elongated elements extend.

6. An electrical switch comprising a stationary contact assembly, a movable contact assembly, means for moving said movable contact assembly into and out of electrical contact with said stationary contact assembly, a terminal for a line conductor, and means for conducting electrical energy from said terminal to said movable contact assembly, said means comprising a pair of links pivotally connected together and pivotally attached to said terminal and said movable contact assembly, pairs of elongated, substantially rigid elements associated with one of said links and contacting at their opposite ends with opposite sides of a part of the other link and a part of said terminal for conducting electrical energy from said terminal to said other link, and a member secured to the link with which the elongated elements are associated for supporting said elongated elements, said member being provided with openings through which said elongated elements extend, said opposite ends of said pairs of elongated elements being displaced from alignment with the central portions of the elongated elements whereby said end portions contact with said parts of said other link and the terminal with considerable compressive force.
